UNITED STATES PATENT OFFICE.

DAVID A. GRANT, OF RALEIGH, CANADA.

LAND-ROLLER.

SPECIFICATION forming part of Letters Patent No. 510,785, dated December 12, 1893.

Application filed April 25, 1893. Serial No. 471,834. (No model.)

To all whom it may concern:

Be it known that I, DAVID A. GRANT, of Raleigh, in the county of Kent, Province of Ontario and Dominion of Canada, have invented a new and useful Improvement in Land-Rollers, of which the following is a full, clear, and exact description.

My invention relates to an improvement in land rollers, and it has for its object to provide a means whereby a number of rollers may be coupled together and used as one, and whereby the rollers may be coupled in sets, these sets being connected with a common frame.

A further object of the invention is to provide a land roller of simple, durable and economic construction which may be used upon ground no matter how undulating or rough, and which may also be successfully employed whether the ground be dry or wet.

It is another object of the invention to provide scrapers for the various rollers, the scrapers of each set being capable of independent manipulation, the driver or manipulator of the roller being able to bring all of the scrapers into requisition, or any one of them, as occasion may demand.

The invention consists in the novel construction and combinations of the several parts, as will be hereinafter fully set forth and pointed out in the claims.

Reference is to be had to the accompanying drawings forming a part of this specification, in which similar figures and letters of reference indicate corresponding parts in all the views.

Figure 1 is a partial plan view and partial horizontal section of the roller. Fig. 2 is a front elevation thereof, one end being in vertical section and likewise the tongue. Fig. 3 is an end view of the roller; and Fig. 4 is a vertical longitudinal section taken essentially on the line 4-4 of Fig. 1.

In carrying out the invention four hollow drums A, are usually employed in the construction of a roller. These drums are open at both ends and are preferably made of metal. Each drum is provided with one or more, preferably two hubs 10, located within it at its center, a connection being effected between the hubs and the drums through the medium of spokes 11 or their equivalents. Each two rollers are coupled by a shaft 12 and

a sleeve 13 through which the shaft passes, the shaft extending beyond the ends of the sleeve and threaded at its extremities, being provided at those points with lock-nuts 14 and washers 15. At the center of each sleeve a box 15^a, is formed, the upper section of the box being removable, as shown in Figs. 1 and 4, the lower portion constituting an integral portion of the sleeve. The center of this box is adapted to be immediately opposite the center of the space between the two drums carried by the sleeve and shaft on which the box is secured, as shown in Figs. 1 and 2, and the drums of a set are properly spaced by washers 16 or their equivalents being placed upon the sleeves 13, one at each side of the box.

The two sets of rollers are connected by a frame B; this frame comprises a front bar 17, located in front of the central portion of the two sets, a rear bar 18, and two side bars 19 and 20. All of the bars are preferably made flat with the exception of the side bars, which at their central portions are made round in cross section in order that they may fit properly in the boxes 15. Thus it will be observed that the frame is somewhat rectangular in cross section and is capable of being rocked upon the shafts 12, as the boxes supporting the frame are connected with the sleeves which have free movement upon the shafts.

The frame B, is adapted to support a platform C, and this platform is ordinarily supported by yoke-like uprights 18^a, which are secured to both the front and rear bars of the frame B. Upon the platform C the driver's seat 21, is erected; and adjacent to or in front of the driver's seat two foot levers 22 and 23, are located, the levers being journaled in suitable bearings upon the platform; and the levers extend from the center thereof in opposite directions transversely across the platform and thence downward at its sides, each lever being provided with a foot treadle at its upper end, against which the driver may exert pressure. Each lever 22 and 23 at its lower end, is connected by a link 24 with a lever arm 25. The lever arms 25, extend downward and rearward in a curved line, as is best shown in Fig. 3; and as fully illustrated in Fig. 3, each lever arm is bifurcated at its lower end in order that the bifurcated or forked lower portion thereof may be ful-

crummed upon sleeves 26, carried by the rear bar 18 of the frame B, as the lever arms are adapted to be carried to and from the rear face of the drums A. Each lever arm has secured to its lower end a scraper 27, the scraper being of angular construction as is best shown in Fig. 3; and the scraper carried by each lever arm is adapted to engage with one connected set of drums A, as shown in Fig. 1. 5

10 The lever arms 25 are guided in their movement, being made to pass through eyes formed upon guide rods 29, also attached to the boxes and extending rearwardly therefrom in a horizontal position, as shown in Fig. 2. Thus it 15 will be observed that when the driver presses against the treadles of the levers 22 and 23, the scrapers will be carried against the drums, and will remove from the drums any soil that may cling thereto; while when the treadles are 20 in the upright position shown in Fig. 2, which is their normal position, the scrapers are carried out of connection with the drums and occupy the position illustrated in Fig. 3. It will be further observed that as the frame B 25 is as it were, fulcrumed upon the connecting medium of the sets of drums, the roller may be readily drawn ahead over exceedingly rough or undulating ground without injury or inconvenience to the team drawing it, since 30 the drums will accommodate themselves to the inequalities of the ground and the frame will accommodate itself in the same manner. The pole 30 is located at its rear end in a socket 31, formed upon the central portion of 35 the front bar 17 of the frame, and braces 32, arranged in the shape of a truss are attached at their rear ends to the front bar 17 near the ends thereof; and at the central portion of the truss brace a socket 33, is formed, through 40 which the pole is also passed. A hammer strap 34, is connected with the pole between the sockets 31 and 33, through the medium of a removable pin 35; and the hammer strap is connected with the brace and with the pole 45 by passing a pin 36, also removable, through the socket 33 and the pole, as shown best in Fig. 1. Thus it will be observed that the pole may be readily removed from connection with the roller when the latter is not required for 50 use. The drums may, as shown in dotted

lines in the drawings, be provided with spurs secured in either a positive or a removable manner to their outer faces, and for example, the spurs may be attached to segmental plates and the plates be secured to the drums. 55 When the spurs are employed the levers, the arms, the guides and the cleaners, are dispensed with. The spurs make the drums effective clod crushers.

Having thus described my invention, I 60 claim as new and desire to secure by Letters Patent—

1. In a land roller, the combination, with a series of drums arranged end to end and at short intervals apart, shafts connecting each 65 two drums, and a sleeve mounted loosely on each shaft and extending through both hubs of a drum, of a frame of substantially rectangular construction, the frame being pivotally connected with the sleeves, a truss brace connected with the forward end of the frame, and sockets formed upon the forward end of the frame and the truss brace, the said sockets being adapted to receive a pole, as and for the purpose set forth. 75

2. In a land roller, the combination, with a series of drums arranged end to end and at short intervals apart, shafts connecting each pair of drums, and a sleeve held to turn upon each of the said shafts, the sleeves having 8c boxes secured to their central portions, of a frame of essentially rectangular construction, the side bars of which are clamped in the boxes, a platform supported by the frame, foot levers journaled upon the platform, lever 85 arms located below the platform, said arms being bifurcated at their lower ends and fulcrumed upon the rear part of the frame, a link connection between the foot levers and the lever arms, guides supported by the frame, 90 through which the links and the lever arms have movement, and scrapers carried by the lower ends of the lever arms, each scraper being adapted for engagement with the rear portion of a pair of drums, as and for the 95 purpose set forth.

DAVID A. GRANT.
